J. SYLVAN

TABLE

Filed Jan. 21, 1924

UNITED STATES PATENT OFFICE.

JOSEPH SYLVAN, OF CICERO, ILLINOIS.

TABLE.

Application filed January 21, 1924. Serial No. 687,421.

To all whom it may concern:

Be it known that I, JOSEPH SYLVAN, a citizen of the United States, and a resident of Cicero, in the county of Cook and State 5 of Illinois, have invented certain new Improvements in Tables; and I do hereby declare that the following is a full, clear, and exact description thereof, reference being had to the accompanying drawings, and to 10 the letters of reference marked thereon, which form a part of this specification.

This invention relates to improvements in tables and consists of the matters hereinafter described and more particularly pointed out 15 in the appended claims.

The primary object of the invention is to provide a new, novel and sanitary table, especially adapted for use in restaurants and like places, which table is so constructed as 20 to embody not only a convenient drinking water service, but also a service for the washing or cleansing of the hands before or after eating.

Other objects of the invention as well as 25 the many advantages will more fully appear as I proceed with my specification.

In the drawings:—

Fig. 1 is a transverse vertical section through a table embodying my invention. 30 Fig. 2 is a horizontal sectional view through the table as taken on the line 2—2 of Fig. 1.

Fig. 3 is a detail horizontal sectional view as taken on the line 3—3 of Fig. 1.

Fig. 4 is a detail vertical sectional view as taken on the line 4—4 of Fig. 2.

Referring now in detail to that embodiment of the invention illustrated in the accompanying drawings:—5 indicates as a 40 whole the frame of the table, and 6 the top for the table. The frame 5 comprises a plurality of upright legs 7, 7 (there usually being four of such legs as shown herein) which legs are connected together at their top ends by horizontal frame bars 8. Said frame bars are preferably made of angle iron, with their vertical flanges flush with the outer surfaces of said legs and with their horizontal flanges directed inwardly. 45

Associated with the frame bars 8 and spaced a suitable distance below the same, are angle bars 9, 9 of smaller cross section, which 50 contact with the frame bars 8 to rigidly hold the legs in the proper spaced relation. Preferably, the inner vertical flanges of the angle

bars 9 are flush with the inner surfaces of said legs while the horizontal flanges thereof are directed outwardly.

The table top 6 which may be either round or rectangular is preferably made of a transparent material such as glass. When made of glass, the top is secured to the frame as follows:—Fixed to the upright flange of each of the frame bars 8, 8 is a plurality of angle clips 10 with their top horizontal flanges 11 flush with the like flanges of the associated bars 8 but directed outwardly, as shown in Fig. 1. Bolts 12 pass through suitable openings in the table top and through the flanges 11, 11 with the heads of the bolts flush with the top surface of the table top. Yielding gaskets 13 are interposed between the flanges 11 and the top 6 while gaskets 14 of similar material are interposed between the heads of said bolts and said table top. When the nuts 70 associated with said bolts are drawn up snug against the under side of the flanges 11, the top is rigidly secured to the frame and there is no danger of cracking or otherwise injuring said table top. 75

In the table top 6 is provided a centrally disposed opening 15 in which is located a basin 16 having a bottom wall 17 arranged in a plane below the table top and having a radial flange 18 at its top which overhangs 80 that part of the table top about the opening 15, a yielding gasket 19 being interposed between said flange and table top. Into the bottom wall of the basin is threaded a plurality of equally spaced nipples 20 to which 85 are connected radially disposed outwardly extending pipes 21, arranged in planes midway between the table legs 7. The outer ends of the pipes are bent downwardly, as shown in Fig. 1. 90

Supported on the angle bars 9 is a large comparatively shallow pan 22 which includes a slightly tapered bottom wall 23 and an upright annular rim flange 24. Made integral with said pan in planes extending 100 through diagonally opposite legs 7 are triangular shaped pockets or receptacles 25. Each pocket includes a top wall 26 and converging side walls 27, the bottom walls of said pockets being formed by parts of the 105 bottom wall 23 of the pan 22. Each pocket opens through the flange 24, as shown at 28 in Fig. 4, and provides a convenient receptacle for napkins 29.

Made integral with the bottom wall 23 of 110

- the pan 22 at its center, is another basin-like member 30 having a bottom wall 31 and a tapered side wall 32, said pan draining into said member 30. 33, 34 indicate up-
 5 right hot and cold water pipes which extend up through suitable collars 35, 35 on the bottom walls of the basins 16 and 30 respectively. Said pipes each have a spigot 36 at its top end which discharges into the basin
 10 16 at the center of the table top. The bottom ends of said pipes extend into a recess 37 in the floor and are there connected by elbows to supply pipes 33^a, 34^a in which are provided suitable shutoff valves 33^b, 34^b respectively. In said pipes 33, 34 are provided union fittings 38 and 39 which may be disconnected when it is desired to move the table to a new location, the valves 33^b, 34^b having been first shut off.
 15 20 40 indicates a waste pipe which is connected at its top end to the basin 30. The bottom end of said pipe extends through the recess 37 in the floor and is connected to a trap 41 which in turn is connected to a pipe 42 leading to a place of disposal, such as a sewer. In the waste pipe 40 are union fittings 43, 44. The recess 37 is closed by two semi-circular plates 45, 45 which have notches 45^a in their meeting edges, to fit
 25 30 around the pipes 33, 34 and 40 respectively, as shown in Fig. 3.

When in use, the cold water spigot 36 supplies drinking water, the overflow or spillage flowing into the basin 16, then through the pipes 21 into the pan 22, whence it drains to the waste pipe 40. Many people, when dining in a public eating house, often desire to rinse or wash their table silverware before using the same. This may be accomplished at my improved table simply by turning on the hot water spigot 36. Drinking glasses may also be rinsed and sterilized in the same manner. The hot water passes to the waste pipe, as does the cold water overflow or spillage, as before described. Should it be desired to wash the hands before or after eating, both the hot and cold water may be turned on to mix in the basin 16 to the desired temperature. Said temperature water will flow through the pipes 21 and will be discharged from the outer bent ends thereof, under any one of which the hands may be washed, while the person is sitting at the table. A napkin 29 may be drawn from the nearest pocket 25 and the hands dried in the usual manner.

It is apparent that my improved table is not only attractive by reason of its novelty but is sanitary in every respect. It may be easily cleaned and also provides a convenient place for the service of drinking water and the cleansing of the table ware or hands which is desired in public eating places.

While in describing my invention, I have referred to certain details of construction

and arrangement of parts, I do not wish to be limited thereto except as may be pointed out in the appended claims.

I claim as my invention:

1. A table comprising in combination, a frame including legs, a top having a centrally disposed opening therein, a basin in said opening, water supply pipes extending up through said basin to discharge water at a point above the top into said basin, a pan mounted on the frame below the top, said pan having an upright peripheral rim, horizontally arranged radially disposed pipes connected with the basin to discharge water therefrom into said pan near its rim, and means for conveying the water in said pan to a place of disposal.

2. A table comprising in combination, a frame including legs, a top having a centrally disposed opening, a basin mounted in said opening and having a bottom wall arranged in a plane below that of said top, water supply pipes extending up through the basin to discharge water at a point above said top into said basin, a pan having an upright rim, mounted on the frame below said top, radially disposed pipes threaded into the bottom wall of the basin to discharge water therefrom into said pan near its rim, and means for conveying the water in said pan to a suitable place of disposal.

3. A table comprising in combination, a frame including legs, a top having a centrally disposed opening therein, a basin for said opening and having a top flange to engage upon the table top and having a bottom wall spaced below the top, a pan mounted on the frame below the top and having an upright rim flange, radially disposed horizontal pipes threaded into the bottom of the basin and having their outer ends bent downwardly to discharge in the pan near its rim, and means for conveying the water in the pan to a place of disposal.

4. A table comprising in combination, a frame including legs, a top, a basin in said top, a pan mounted on the frame below the top and having a rim flange, water supply pipes extending up through the basin to discharge water at a point above the top into the basin, means for discharging water from the basin into the pan near its rim, means carried by the pan and providing napkin pockets which open through the rim of said pan, and means for conveying the water from the pan to a place of disposal.

5. A table comprising in combination, a frame including legs, a top, a basin carried by the top, a pan on the frame below the top and having a rim flange, water supply pipes extending up through the pan and basin to discharge at a point above the top into the basin, radial pipes between said top and pan for conducting water from the basin and to discharge it into the pan near

its rim flange, and a waste pipe connected to said pan adjacent the water supply pipes.

6. A pan for a table of the kind described, having a bottom wall and an upright rim flange, and means providing pockets within the pan near said rim flange, which pockets open through said flange to provide access to said pockets.

In testimony that I claim the foregoing as my invention, I affix my signature in the presence of two witnesses, this 18th day of January, A. D. 1924.

JOSEPH SYLVAN.
